UNITED STATES PATENT OFFICE.

WILLIAM C. WELT, OF ALBIA, IOWA

RAILROAD-TIE.

1,071,674.

Specification of Letters Patent. Patented Aug. 26, 1913.

Application filed March 15, 1913. Serial No. 754,437.

To all whom it may concern:

Be it known that I, WILLIAM C. WELT, a citizen of the United States, residing at Albia, in the county of Monroe and State of Iowa, have invented new and useful Improvements in Railroad-Ties, of which the following is a specification.

The present invention relates to improvements in metallic ties for railroads, and to rail clamps associated with the said ties.

The improvement resides in the construction, combination and operative arrangement of parts set forth in the following description and falling within the scope of the appended claims.

In the drawing: Figure 1 is a view in perspective, illustrating rails supported upon my improved tie, Fig. 2 is a central longitudinal sectional view through the tie, Fig. 3 is a transverse sectional view upon the line 3-3 of Fig. 2, Fig. 4 is a similar sectional view on the line 4-4 of Fig. 2, Fig. 5 is a perspective view of the removable member of the clamp, and Fig. 6 is a view of the blank from which the sliding clamp is formed.

In reducing my improvement to practice, I contemplate the employment of a shell 1 constructed of some suitable metal and which is rectangular or square in cross section. The shell is of a length corresponding approximately with the lengths of the ordinary wooden ties for rails, and the said shell may comprise a casting or may be constructed of a single piece of metal which is bent to the proper shape and which may have its ends connected in any desired or preferred manner. To reinforce the shell 1, I provide a longitudinally extending member which is arranged within the tie and which comprises a central web 2 having its upper and lower edges formed with heads 3 and 4 respectively. The heads are arranged at an angle from the opposite sides of the web, and may have their edges secured to the corners of the shell 1, or the said reinforcing element may be formed integral with the shell. The heads 3 and 4 are preferably arranged in angular relation to the web 2; that is, both of the wings forming the heads are disposed at opposite angles from each other and from the web. The edges of these wings abut with the inner corners of the shell 1, but as neither the top nor bottom of the shell contacts with the central portion of the reinforcing member,

the shell is permitted a certain amount of elasticity, which permits of a "give" to the rails, so that the same will not snap or become broken when the rolling stock passes over the portions of the rails secured to the ties. The upper face, which may be designated by the numeral 5, of the tie is provided adjacent its opposite ends with integrally formed inwardly inclined members 6 which are disposed transversely of the tie and which provide engaging lips for the outer longitudinal edges of the base flanges of the rails R.

The numeral 7 designates the slidable clamp members which are adapted to coact with the lips 6 for sustaining the rails upon the tie. The clamps 7 may be, and preferably are, constructed of a single piece of suitable material, and comprise each a top 8 of a width corresponding with the width of the tie, said tie being provided with downturned flanges 9, and the said flanges being inturned to provide tongues 10 which are disposed within the elongated longitudinally arranged openings 11 provided in the sides of the said ties, adjacent the ends of said ties. The top is preferably slotted at its juncture with its sides, the said slotted portion being upturned to provide a rail base flange-engaging lip 12. The top of the tie is provided, adjacent its ends, and forward of its lips 6 with elongated openings 13 and disposed within the tie and adapted to rest within the channel, provided by the upper face of the reinforcing member and the oppositely inclined wings forming the upper head of said reinforcement, is a threaded rod 14 which has its inner extremity upset and passing through the opening 13 and secured to the top member of the clamp 7. The tie is further provided, upon its top face and between its ends and lips 12 with openings 15 through which extend the upper portions of nuts 16 which engage with the threaded rods 14. By such an arrangement, it will be noted that the sliding clamp 7 may be readily drawn toward the lip 6 to cause the lip of the clamp to tightly engage with the inner base flange of the rail and to force the outer base flange into tight engagement with the lip 6 when the nut 16 is rotated upon the rod 14 in one direction, and further, that when the nut is rotated in an opposite direction, the clamp 7 will be drawn away from the lip 6 to permit of the removal of

the rails from the ties. It will be further noted that by constructing a tie as above described, an exceedingly strong device may be manufactured which will provide the desired amount of elasticity to the rails and which, further, may be constructed extremely light in weight, so that the same can be readily handled.

Having thus described the invention, what I claim as new is:

- 10 1. A rail tie comprising an outer metallic shell, an inner reinforcing member for the shell, said member comprising a web having oppositely arranged heads, said heads being connected with the inner corners of the tie, and means associated with the tie for sustaining the rails upon the tie.
- 15 2. A rail tie comprising an outer cross sectional rectangular shell, a reinforcing member centrally arranged within the shell, said member comprising a web having its opposite edges formed with heads, the said heads being arranged at angles from the web and having the longitudinal edges se-
- 20

cured to the inner corners of the tie, and means associated with the tie for retaining the rails upon the tie.

3. A tie comprising a metallic shell, a central reinforcing member within the shell, and said member being connected only to the corners of the tie, the rail engaging means associated with the tie.

4. A metallic tie including a shell, a reinforcing member within the shell, said reinforcing member including a central web, and heads comprising oppositely disposed angularly arranged wings which have their longitudinal edges secured to the corners of the tie, and rail engaging members associated with the tie, and rail engaging means associated with the tie.

In testimony whereof I affix my signature in presence of two witnesses.

WILLIAM C. WELT.
